(57) **CLAIM**

What is claimed is the ornamental design for a cap with visor, as shown and described.

DESCRIPTION

FIG. 1 is a perspective view of a cap with visor, showing the new design;

FIG. 2 is a top plan view thereof;

FIG. 3 is a front elevational view thereof;

FIG. 4 is a left-side elevational view thereof;

FIG. 5 is a rear elevational view thereof;

FIG. 6 is a right-side elevational view thereof; and,

FIG. 7 is a bottom plan view thereof.

The broken lines showing a person in FIG. 1 are included for the purpose of illustrating the invention in use, and form no part of the claimed design. The broken lines showing an embroidered logo in FIGS. 1-4 and 6 depict environmental matter, and form no part of the claimed design.
